ALEXANDER W. COPLAND

BY *James Whittmore*
ATTY.

UNITED STATES PATENT OFFICE.

ALEXANDER W. COPLAND, OF DETROIT, MICHIGAN.

DEPOSITING-MACHINE.

No. 806,110.

Specification of Letters Patent.

Patented Dec. 5, 1905.

Application filed November 7, 1904. Serial No. 231,723.

To all whom it may concern:

Be it known that I, ALEXANDER W. COPLAND, a citizen of the United States, residing at Detroit, in the county of Wayne and State 5 of Michigan, have invented certain new and useful Improvements in Depositing-Machines, of which the following is a specification, reference being had therein to the accompanying drawings.

10 The invention relates to improvements in depositing-machines intended for bakery and confectionery work, and comprises a material-hopper, a piston or pistons having their discharge ends arranged adjacent to the hopper-section, a discharge-nozzle below, a reciprocating valve for connecting the hopper with the cylinder or for shutting off the hopper and connecting the cylinder with the discharge-nozzle, and a carrier which varies and lowers.

15 The invention further consists in the construction, arrangement, and combination of the various parts, as more fully hereinafter described, and particularly pointed out in the claims.

20 In the drawings, Figure 1 is a side elevation of my machine, showing the lower part of the hopper and the plunger-cylinder and discharge-nozzle in section. Figs. 2, 3, 4, and 5 are sections through the cylinder, hopper, and

25 nozzle, showing the different positions of the plunger-valve and nozzle.

A is the frame of the machine, which supports the operating parts, including the main drive-shaft B, which is driven from any suitable 30 source of power. On the frame are the side brackets B', which support the hopper C, having a discharge-throat C' at the bottom. On the front face of the base of the hopper I secure the cylinder or cylinders D. In this case I

35 have shown the base of the hopper provided with a flat face α , to which the cylinder (which is in the shape of a U-shaped casting) is bolted by bolts b at the ends, leaving a space between in which is located the piston E. The cylinder has a foot E', extending down below the base of the discharge-port from the cylinder, and the hopper has a foot F opposite the foot E'. In these two feet are formed suitable 40 guides, in which slides the valve G, having the U-shaped port G' therethrough. Below the valve is secured the nozzle-plate H, preferably by means of the clamping-plate F'. In the

nozzle-plate are a series of nozzles c, having the rearwardly-inclined discharge d. The valve is reciprocated by means of the levers I, 55 one at each side of the machine, which are connected to the valve by links I', these levers being fulcrumed in the base of the machine on the shaft d'. On the shaft d' is secured the rock-arm d'', which has the roller d''', adapted 60 to engage and be operated by a cam having a camway e on the drive-shaft B''. This construction causes the shaft d' to be rocked, and with it the levers I, which causes the valve to reciprocate back and forth. In one position, 65 Fig. 5, the port G' of the valve will cut off the port h through the nozzle and will connect the discharge-throat of the hopper with the cylinder and in the other position, Fig. 2, will cut off the discharge-throat of the hopper and 70 connect the cylinder with the discharge nozzle or nozzles. The piston is actuated by the two connecting-rods J, one at each end, which connect to the slotted lever J', secured to the shaft J''. This shaft has a rock-arm K, which 75 is connected by the connecting-rod K' with an eccentric L on the shaft B'', causing the piston to be vertically reciprocated. Its upward movement draws the material from the hopper (the valve being in the proper position) 80 and the downward movement discharges the material through the nozzles, the valve being shifted in the meantime.

M is a table pivoted at M' at one end, and at 85 its other end is supported on the rods N, which at their lower ends are connected to the rock-arms N', secured to the shaft N'' in the base of the machine. To this shaft is connected the rock-arm O, which has a roller O' bearing against the cam P on the shaft B'', constructed 90 so that the table will be tilted on its pivot, being raised and lowered at the proper times. Running over the table is an endless carrier Q, which may be in the shape of a belt of any desired construction. This carrier runs over the 95 wheels or rolls S and S' at opposite ends and is actuated at the proper interval by means of the pawl i on the lever k , journaled on the shaft l and actuated by a bell-crank lever m, to which the lever k is connected by the link n. 100 The bell-crank lever m is operated by engagement with the cam o on the shaft B'' in one direction and by the spring o' on the reverse direction.

- The parts being thus constructed their operation is as follows: The hopper being filled with the desired material the pans are put on the carrier running over the table and beneath the nozzles, the piston is driven upward through the connections described, the valve at that time connecting the cylinder with the hopper, and the material will be drawn into the cylinder below the piston. The valve will then be shifted to the position shown in Figs. 1 and 2, registering the port G' in the valve with the port h in the nozzle, which will cause the material as the piston descends to discharge from the nozzle onto the pan beneath.
- When the deposit has been made, the valve will be shifted to cut off the connection between the cylinder and the nozzle.
- By reference to Figs. 2, 3, 4, and 5 the operation of cutting off the dough in the nozzle from that deposited will be understood. As soon as the valve closes the table begins to lower, and at the same time the feed-apron moves forward, which will lower the face of the deposit across the rear face of the nozzle and also carry back onto the deposit any string, thread, or connection there may be between the dough in the nozzle and that deposited. This movement being comparatively rapid will not only deposit the thread or connecting filament on the deposit, but also quickly sever that thread which would otherwise connect the nozzle with the deposit. These operations, as previously described, are illustrated in diagram in Figs. 2, 3, 4, and 5.
- The apron feeds forward beyond the deposit already made, and the table is again lifted in proximity to the nozzle for a second deposit adjacent to the first.

It is well understood in the manufacture of these machines that I may employ a single nozzle for a single deposit or that I may employ a series of nozzles arranged side by side, and I may employ a single piston or a series of pistons, one for each nozzle, and this I think will be readily understood from the known construction in such devices without further illustration. I prefer, however, to use a single piston and a single port in the valve and a single slot in the discharge-throat of the hopper, for the reason that it reduces friction and also is more readily cleaned.

By removing the screws which hold the clamping-plate F' the valve may be removed, and it is obvious that by removing the bolts b the cylinder, piston, and nozzle-plate may be readily detached for cleaning purposes.

I have made the rods N adjustable, and in order to insure an equal adjustment of both I mount sprockets on the adjusting-sleeves and connect the sprockets by a chain, as clearly shown in Fig. 1. To secure equal adjustment of the adjusting-shafts connected to the links

J, I mount sprockets on these shafts and connect them by a chain in the same manner.

What I claim as my invention is—

65

1. In a depositing-machine, the combination of a stationary material receptacle and cylinder having their discharge-ports side by side, a perforated nozzle-plate below the same and a valve between these discharge-ports and said plate having an opening therein, means for reciprocating said valve to connect the two discharge-ports and close the port in the nozzle-plate, or to shut off the discharge from the receptacle and connect the cylinder-port 75 with the perforations in the plate.

2. In a depositing-machine, the combination of a hopper having a vertical discharge-port, a cylinder arranged beside the same, a piston therein, a horizontally-reciprocating valve-plate below the discharge-ports from the cylinder and receptacle having an opening or openings therein adapted to connect or disconnect the two ports, a perforated plate below the valve-plate, the ports therein adapted 80 to be registered with the openings in the valve-plate when the hopper connection is shut off and nozzles on the perforated plate.

3. In a depositing-machine, the combination of a hopper, having a discharge-port at the bottom, and having a plain face a on one side thereof, of a cylinder D formed in the shape of a U-shaped casting bolted against the face a , a piston in the cylinder thus formed, a nozzle-plate detachably secured to the base of the 95 hopper and a reciprocating valve between the nozzle-plate and the hopper and the cylinder discharge, for the purpose described.

4. In a depositing-machine, the combination of a material-hopper, a nozzle-plate below the 100 same, means for discharging material from the hopper to said nozzle-plate intermittently, a reciprocating table below the nozzle-plate, means for feeding the deposited material on said table, the parts being combined so that 105 as the table is lowered the deposits are fed forward whereby the deposit will move downwardly and forwardly in relation to the nozzle for the purpose described.

5. In a depositing-machine, the combination 110 of a material-receptacle, the nozzle-plate below the same, nozzles thereon having a rearward discharge, a reciprocating table below the nozzle-plate, means for feeding the material along the table, the table-reciprocating 115 means and the feeding means being so combined that the forward feed will take place as the table lowers for the purpose described.

6. The combination with a material-receptacle and with a nozzle-plate below the same, of means for intermittently discharging material from the receptacle to said nozzle-plate, the nozzles on said plate having a passage h and an inclined face d , and means for feed-

ing the deposited material downward and forward in relation to said nozzle for the purpose described.

7. In a depositing-machine, the combination of a discharge-spout, feed mechanism for intermittently depositing charges of batter or dough therefrom, and means for moving the deposit beneath the nozzle by a downward-

and-forward movement, for the purpose described.

In testimony whereof I affix my signature in presence of two witnesses.

ALEXANDER W. COPLAND.
